UNITED STATES PATENT OFFICE.

ROBERT W. KROBITZSCH, OF SAN FRANCISCO, CALIFORNIA, ASSIGNOR TO SUNSET FEATHER COMPANY, OF SAN FRANCISCO, CALIFORNIA.

FEATHER-CLEANING MACHINE.

Application filed June 16, 1926. Serial No. 116,410.

My invention relates to improvements in a machine for cleaning feathers and the like, wherein feathers, introduced into a cleaning chamber by an air current, are subjected to the action of a beating element to remove dust and dirt, the dust and dirt being drawn from the chamber by suction without loss of feathers.

The primary object of my invention is to provide an improved feather cleaning machine, whereby feathers may be more efficiently cleaned.

Another object is to provide an improved machine which will obtain a more thorough cleaning of the feathers and a more complete removal of dirt, dust and refuse therefrom.

Another object is to provide an improved machine which will effectively remove heavy refuse and foreign matter from feathers prior to the introduction of said feathers into a cleaning chamber.

A further object is to provide an improved machine, wherein the dust outlet may be effectively cleaned and kept open to permit an efficient removal of dust and dirt from the chamber during the cleaning operation.

A still further object is to provide an improved machine which is simple and efficient and which can be economically constructed and operated.

I accomplish these and other objects by means of the improved device disclosed in the drawings forming a part of the present specification, wherein like characters of reference are used to designate similar parts throughout said specification and drawings and in which,

Fig. 1 is a broken transverse vertical section of the machine, and

Fig. 2 is a broken longitudinal vertical section of the machine.

Referring to the drawings, the numeral 1 is used to designate in general a cleaning chamber arranged to receive a quantity of feathers for cleaning. The feathers are introduced into the chamber 1 through a plurality of substantially vertical conduits 2, connected at their upper ends to a common supply conduit 3 arranged to receive feathers

introduced thereinto from a suitable hopper, 50 not shown, the feathers being carried through the conduits 3 and 2 by a current of air directed therethrough by a suitable blower, not shown, connected in any convenient manner. Lateral extensions 4 are 55 connected into the vertical conduits 2 near the bottoms thereof, said extensions opening into the lower portion of the chamber 1.

The conduits 2 are extended downwardly past the lateral extension 4 to form trap 6, 60 arranged to receive heavy refuse in a manner hereinafter more fully explained; the bottom of said downwardly extending portions being closed by means of suitable removable covers 7, to permit the removal of refuse 65 from the traps. Windows 8, normally closed by suitable covers 9 are preferably formed in the trap portions 6, whereby the interior of the traps and the conduits may be observed if desired.

A beating element is mounted within the lower portion of the chamber 1, said beating element consisting of a plurality of radially disposed arms 11 secured upon a shaft 12 extending longitudinally through the lower portion of the chamber 1, said arms being preferably curved and split at the outer ends, as at 13, to obtain an increased stirring and beating effect. The arms are spaced along the shaft 12 and preferably arranged with an arm opposite each conduit 4, whereby feathers introduced through said conduits will be subjected immediately to the action of the beating arms 11. The arms are preferably arranged spirally along the shaft, the arms being angularly spaced substantially ninety degrees apart.

An opening 14 is formed in the top of the chamber 1, said opening being covered by a suitable screen 16. A housing 17 is mounted upon the top of the chamber 1 to enclose the screened opening 14. A suction connection 18 opens into one side of the housing 17, said connection being widened at its upper end to embrace substantially the entire length of the housing 17. Suction is induced in the connection 18 by means of a blower or other suitable means, not shown, said suction not

operating to draw dust and dirt out of the chamber 1 through the screen 16, hereinafter more fully explained.

In order to keep the screen 16 clean and 5 to prevent the accumulation of feathers upon the screen, I provide brushes 19 secured upon arms 21, which are in turn secured upon a shaft 22 extending longitudinally through the upper portion of the chamber 1, parallel 10 to the shaft 12. The brushes 19 are arranged to engage the inner surface of the screen 16 and operate to brush away the feathers and to loosen any dirt or dust clinging to the screen, whereby the screen may be kept open 15 to permit the free movement of dust and dirt therethrough.

The upper surface of the screen is preferably cleaned by means of brushes 23, slidably mounted within the housing 17 and 20 arranged to be reciprocated by means of arms 24 pivotally engaging links 26 connected through the housing 17. The backs of the brushes 23 have openings 28 formed therethrough to permit a free circulation of 25 air and to prevent the brushes from forming any material obstruction to the movement of dust and dirt outwardly from the chamber 1. The brushes are slidably supported upon slats 29 mounted at intervals 30 to brace the screen 16.

A suction conduit 31 is connected into the lower portion of the chamber 1, said connection being normally closed and arranged to be opened and suction applied for withdrawing feathers from the chamber 1 after 35 said feathers have been cleaned.

The chamber 1 preferably has its top and bottom made semi-circular in transverse cross section, the arms 11 being of a length 40 such that a slight clearance is provided between the ends of said arms and the bottom of the chamber, while the brushes 19 are arranged to sweep the inner surface of the top portion of the chamber and the screen 17, which is shaped and held concentric with the top of the chamber by slats 29. The chamber is preferably constructed from suitable sheet metal and supported upon a suitable structural iron frame 32.

50 The shafts 12 and 22 extend outwardly through the ends of the chamber 1 and are provided with pulleys 33 and 24 respectively. A belt 36 is mounted over the pulleys 33 and 34, whereby the shafts are rotated simultaneously, power being delivered to one of the shafts in any suitable manner, not shown. A belt 37 is connected over pulleys 38 and 39 mounted upon the shafts 22 and 28, respectively, for rotating the shaft 28 to operate 55 the brushes 23.

In operation, the feathers are fed into the supply conduit 3 in any convenient manner and carried by a moving current of air downwardly through the conduits 2. The

air current passes into the chamber 1 65 through the lateral extensions 4, the feathers being carried by the air current into the chamber. Any heavy refuse present is not diverted by the air current and drops downwardly into the trap 6. 70

As the feathers enter the chamber 1 they are stirred and beaten by the arms 11, which are operated at sufficient speed to beat all dust and dirt out of the feathers and to keep the feathers in constant agitation within the chamber. As the dust and dirt is beaten out of the feathers it is drawn upwardly by the upward circulation of air toward the opening 14 in the top of the chamber, said dust and dirt being drawn 80 through the screen and outwardly through the conduit 18 by the suction applied therethrough.

Heavy particles of dirt or refuse are thrown outwardly through the conduit extensions 4 by centrifugal force and are received in the traps 6. The feathers being heavier than the dust particles remain for the most part within the lower portion of the chamber. A portion of the feathers are 90 carried upwardly into the upper portion of the chamber, such feathers being prevented from passing outwardly with the dirt and dust through the opening 14 by the screen 16. The suction operating through the connection 18 tends to hold some of the feathers against the inner surface of the screen 16. The rotating brushes 19 sweeping across the inner surface of the screen 16 remove the feathers from said screen and prevent the 95 accumulation of the feathers in sufficient quantity to materially interfere with the movement of dust and dirt outwardly through the screen. Occasionally feathers become lodged upon the screen by reason of 100 the movement of the quill portions through the interstices of the screen. The brushes 23 are reciprocated across the top of the screen to dislodge said feathers and force the same back into the chamber 1. 105

In practice steam is introduced into the chamber 1 through suitable steam connections 41 opening into the lower portion of the chamber, and warm or cool air currents introduced through the conduits 3 while the feathers are being agitated within the chamber. In my preferred practice, steam is first introduced immediately after a charge of feathers has been introduced into the chamber. A current of cold air is then introduced to condense the steam and partially dry the feathers. Steam is then again introduced for a limited period, followed by the introduction of a warm air current to thoroughly dry the feathers. 115

After the feathers have been thoroughly cleaned the suction conduit 31 is opened and suction applied in any convenient manner to 120

draw the feathers out of the chamber 1, the feathers being carried by a current of air resulting from an incoming current entering the chamber through the conduits 2 and passing outwardly through the suction conduit 31.

While I have illustrated and described what I now regard as the preferred embodiment of my invention, the device is, of course, subject to modification in the specific details of construction. I therefore do not wish to restrict myself to the specific construction disclosed, but desire to avail myself of all modifications which may fall within the scope of the appended claims.

Having thus described my invention what I claim as new and desire to secure by Letters Patent is:

1. A feather cleaning machine comprising a chamber; a beating element mounted within the lower portion of the chamber; means for introducing feathers to be cleaned into the chamber; suction means connected to an opening formed in the top of the chamber to carry away dust and dirt separated from the feathers; a screen covering said opening; means mounted within the upper portion of the chamber for cleaning the inner side of screen to prevent the lodging of feathers therein; means mounted adjacent the outer side of the screen and operating simultaneously with the inner cleaning means for displacing feathers not removed by said inner cleaning means; and means for withdrawing the feathers from the machine.

2. A feather cleaning machine comprising a chamber; a beating element mounted within the lower portion of the chamber; means for introducing feathers to be cleaned into the chamber; suction means connected to an opening formed in the upper portion of the chamber for carrying away dust and dirt separated from the feathers; a screen covering said opening; means rotatably mounted within the upper portion of the chamber and arranged to engage the inner surface of the screen to clean the same; reciprocating means engaging the outer surface of the screen and operating simultaneously with the inner cleaning means for dislodging feathers therefrom; and means for withdrawing the feathers from the machine.

3. A feather cleaning machine comprising a chamber; a beating element mounted within the lower portion of the chamber; means for introducing feathers to be cleaned into the chamber; suction means connected to an opening formed in the upper portion of the chamber for carrying away dust and dirt separated from the feathers; a screen covering said opening; brushes rotatably mounted within the upper portion of the chamber and

arranged to engage the inner surface of the screen for cleaning the same; brushes mounted adjacent the outer surface of the screen and operating simultaneously with the inner cleaning means for dislodging feathers therefrom; and means for withdrawing the feathers from the machine.

4. A feather cleaning machine comprising a chamber; means for introducing feathers into the chamber to be cleaned; a shaft mounted within the lower portion of the chamber; a plurality of beating arms secured upon the shaft; suction means connected to an opening formed in the upper portion of the chamber for carrying away dust and dirt separated from the feathers; a screen covering the opening; a second shaft mounted within the upper portion of the chamber; brushes mounted upon the shaft and arranged to be moved thereby to engage the inner surface of the screen; means connected between the shafts whereby said shafts may be rotated simultaneously; and means for withdrawing the cleaned feathers from the chamber.

5. A feather cleaning machine comprising a chamber; means for introducing feathers into the lower portion of the chamber to be cleaned; a suction conduit connected to an opening formed in the upper portion of the chamber; a screen covering the opening; shafts mounted within the upper and lower portions of the chamber and extending longitudinally therethrough; means for rotating the shafts; a plurality of beating arms secured upon the lower shaft for beating the feathers to remove dust and dirt therefrom, said dust and dirt being drawn off through the suction conduit and the feathers retained within the chamber by the screen; brushes secured upon the upper shaft and arranged to engage the inner surface of the screen for cleaning the same and to prevent the accumulation of feathers thereon; means engaging the outer surface of the screen and operating simultaneously with the brushes for dislodging feathers therefrom; and means for withdrawing the cleaned feathers from the chamber.

6. A feather cleaning machine comprising a chamber; a vertically disposed conduit provided with a laterally disposed extension connected into the lower portion of the chamber for introducing feathers and air currents into the chamber; a trap formed by a downward extension of the vertical conduit to catch heavy refuse carried with the feathers; a beating element mounted within the lower portion of the chamber for beating the feathers to remove dust and dirt therefrom; a suction conduit connected to an opening formed in the top of the chamber; a screen covering said opening and arranged to permit the movement of dust and

dirt therethrough and to retain the feathers within the chamber; means for cleaning the screen to prevent the accumulation of feathers thereon; and means for withdrawing the cleaned feathers.

7. A feather cleaning machine comprising a chamber; means for introducing feathers to be cleaned and air currents into the lower portion of the chamber, said means comprising a plurality of vertically disposed conduits having lateral extensions opening into the lower portion of the chamber and having downward extensions forming traps arranged to catch heavy refuse introduced with the feathers; beating means mounted within the chamber for removing dust and dirt from the feathers; means for conducting the dust and dirt away from the chamber; and means for withdrawing the cleaned feathers from the chamber.

8. A feather cleaning machine comprising a chamber; means for introducing feathers to be cleaned and air currents into the chamber, said means comprising a plurality of vertically disposed conduits having lateral extensions opening into the lower portion of the chamber and having downward extensions forming traps arranged to catch heavy refuse introduced with the feathers; beating means mounted within the chamber for removing dust and dirt from the feathers; a suction conduit connected to an opening formed in the upper portion of the chamber for drawing off dust and dirt separated from the feathers; a screen covering the opening; and means for cleaning the screen to prevent the accumulation of feathers thereon.

9. A feather cleaning machine comprising a chamber; means for introducing feathers to be cleaned and air currents into the chamber, said means comprising a plurality of vertically disposed conduits having lateral extensions opening into the lower portion of the chamber and having downward extensions forming traps arranged to catch heavy refuse introduced with the feathers; beating means mounted within the lower portion of the chamber for removing dust and dirt from the feathers; a suction conduit connected to an opening formed in the upper portion of the chamber for drawing off dust and dirt separated from the feathers; and brushes rotatably mounted within the upper portion of the chamber and arranged to engage the inner side of the screen for cleaning the same and to prevent the accumulation of feathers thereon;

10. A feather cleaning machine comprising a chamber; means for introducing feathers to be cleaned and air currents into the chamber, said means comprising a plurality of vertically disposed conduits having lateral extensions opening into the lower

portion of the chamber and having downward extensions forming traps arranged to catch heavy refuse introduced with the feathers; beating means mounted within the lower portion of the chamber for removing dust and dirt from the feathers; a suction conduit connected to an opening formed in the upper portion of the chamber for drawing off dust and dirt separated from the feathers; and brushes rotatably mounted within the upper portion of the chamber and arranged to engage the inner side of the screen for cleaning the same and to prevent the accumulation of feathers thereon; and means engaging the outer side of the screen for dislodging feathers therefrom.

11. A feather cleaning machine comprising a chamber; means for introducing feathers to be cleaned and air currents into the chamber, said means comprising a plurality of vertically disposed conduits having lateral extensions opening into the lower portion of the chamber and having downward extensions forming traps arranged to catch heavy refuse introduced with the feathers; beating means mounted within the lower portion of the chamber for removing dust and dirt from the feathers; a suction conduit connected to an opening formed in the upper portion of the chamber for drawing off dust and dirt separated from the feathers; and brushes rotatably mounted within the upper portion of the chamber and arranged to engage the inner side of the screen for cleaning the same and to prevent the accumulation of feathers thereon; and reciprocating brushes mounted adjacent the outer surface of the screen for dislodging feathers therefrom.

12. In a feather cleaning machine, the combination with a screened outlet arranged to permit the removal of dust and dirt and to prevent the removal of feathers, of brushes mounted adjacent the inner surface of the screen to clean the same and to prevent the accumulation of feathers thereon; and brushes mounted adjacent the outer surface of the screen for displacing feathers inwardly from the screen, said inner and outer brushes being operated simultaneously to engage opposite sides of the screen.

13. In a feather cleaning machine, the combination with a chamber, of means for introducing feathers into said chamber to be cleaned, said means comprising vertically disposed conduits provided with lateral extensions opening into the chamber whereby feathers may be carried by an air current into the chamber; and downward extensions connected to the vertical conduits to form traps to catch heavy refuse introduced with the feathers.

14. In a feather cleaning machine, the combination with a chamber, of means for

introducing feathers into said chamber to be cleaned, said means comprising vertically disposed conduits provided with lateral extensions opening into the chamber whereby feathers may be carried by an air current into the chamber; and downward extensions connected to the vertical conduits to form traps to catch heavy refuse introduced

with the feathers; and removable covers closing the bottoms of the downward extensions whereby traps may be opened for cleaning. ¹⁰

In witness whereof, I hereunto set my signature.

ROBERT W. KROBITZSCH.
